FERRITE ROTATOR DEVICES

Pierre Aegerter, Paris, France, assignor to Compagnie Generale de Telegraphie sans Fil, a corporation of France

Filed Sept. 24, 1959, Ser. No. 842,151

Claims priority, application France Sept. 26, 1958

1 Claim. (Cl. 333—98)

The present invention relates to ferrite rotators. Such rotators usually comprise a ferrite element located in a wave guide coaxially therewith and along the axis of which a magnetic field is directed. This field causes the rotation of the polarization plane of the wave propagating in the guide by an angle depending upon the intensity of the field.

Such ferrite gyrator or rotator devices are frequently used in microwave techniques.

For example, ferrite rotators are used in switching arrangements. The magnetic field is caused, in this case, to vary rapidly between two fixed values.

However, the production of such magnetic fields requires the application of substantial amounts of energy.

The present invention has for its object to avoid this drawback.

A ferrite rotator arrangement according to the invention comprises at least one ferrite rod located along the axis of a wave guide and two electromagnets positioned in alignment with said ferrite rod, respectively at both ends thereof.

The invention will be best understood from the following description and appended drawing, the single FIGURE of which represents, very schematically, a rotator according to the invention.

Referring to the drawing, there is shown a circular wave guide 1, wherein a TE_{11} wave is propagated. Two ferrite rods 2 and 3 are positioned in the guide coaxially therewith. They are held in position by a flared element 4 made of dielectric material such as "Micalex" the internal diameter of this element being made smaller at this place, then increasing progressively at the outer ends of rods 2 and 3 thus to insure a better matching of the rods to the guide. The dielectric constant of this element is chosen as known to be equal to the dielectric constant of the ferrite. Two magnets 5 and 6, the length of which is preferably equal to $\lambda_g/4\lambda$, λ_g being the operating wave length, are positioned between the respective outer ends of rods 2 and 3 and the tapered wall portions of element 4.

Coils 7 and 8 are wound around the guide portions respectively containing magnets 5 and 6. They provide positive or negative pulses for the polarization of mag-

2

nets 5 and 6. The induction in the ferrite rods may be adjusted by controlling the gap between rods 2 and 3 and a ceramic element 9 having the same dielectric constant as the ferrite may be inserted in this gap.

5 The magnetic material for magnets 5 and 6 is selected in accordance with the desired field intensity. For a field of 1000 oersted, cobalt-tungsten steel is generally preferred.

The invention is of course not limited to the embodiment described which has been given solely by way of example.

For example it may be desired to cause the polarization vector to rotate alternately by

$$-\frac{\pi}{2} \text{ and } +\frac{\pi}{2}$$

in such a way that the respective outputs be out of phase 10 by π . In this case positive and negative pulses of equal intensities are alternately fed to both coils 7 and 8, the amplitude of these pulses being selected for alternately creating in magnets 5 and 6 inductions which provide in ferrite rods magnetic fluxes of opposite signs and of the 15 magnitude necessary for rotating the polarization vector by

$$-\frac{\pi}{2} \text{ and } +\frac{\pi}{2}$$

20 respectively.

What is claimed is:

A ferrite rotator for rotating the polarization direction of an ultra high frequency wave comprising in combination; a circular wave guide having an axis; an insulating flared element in said wave guide and having a recess at 25 said axis; a ferrite assembly comprising at least two ferrite rods separated by a gap and extending along said axis, said assembly having two ends; an insulating element in said gap; two magnetic pieces of a ferromagnetic conductive material respectively located at said two ends; and 30 two windings surrounding said pieces for respectively generating polarization fields therein.
